UNITED STATES PATENT OFFICE.

JAMES KARMI DALKRANIAN, OF NEW YORK, N. Y., ASSIGNOR, BY MESNE ASSIGNMENTS, TO UNITED STATES PERSIAN CARPET COMPANY, OF NEW YORK, N. Y., A CORPORATION OF NEW YORK.

PILE-FABRIC LOOM.

No. 858,962.

Specification of Letters Patent.

Patented July 2, 1907.

Application filed March 20, 1905. Serial No. 260,979.

To all whom it may concern:

Be it known that I, JAMES KARMI DALKRANIAN, a citizen of the United States, and a resident of the city of New York, borough of the Bronx, in the county and 5 State of New York, have invented a new and Improved Pile-Fabric Loom, of which the following is a full, clear, and exact description.

The object of the invention is to provide a new and improved pile fabric loom, more especially designed for 10 weaving pile fabrics in any desired design and color and of the oriental rug type, having Persian knots, such for instance as shown and described in the application for Letters Patent of the United States, No. 250,980 filed by me under even date herewith.

15 The invention consists of novel features and parts and combinations of the same, as will be more fully described hereinafter and then pointed out in the claims.

A practical embodiment of the invention is represented in the accompanying drawings forming a part of 20 this specification, in which similar characters of reference indicate corresponding parts in all the views.

Figure 1 is a side elevation of the improvement; Fig. 2 is an end elevation of the same; Fig. 3 is an enlarged plan view of one end of the lay; Fig. 4 is an enlarged 25 plan view of the looper; Fig. 4A is an end view of the clamping terminals of the looper; Fig. 4B is a perspective view of one of the tuft yarn tubes in engagement with a clamping terminal, to deliver the end of the pile thread to the clamping terminal; Figs. 5, 6, 7 and 8 are 30 enlarged sectional side elevations of the improvement, illustrating the successive steps in the formation of the pile fabric; Fig. 9 is a diagrammatic view of the improvement shown in Fig. 8; Fig. 10 is a sectional side elevation of the improvement, showing a subsequent 35 step in the formation of the fabric; Fig. 11 is a diagrammatic plan view of the same; Figs. 12, 13, 14, 15, 16 and 17 are sectional side elevations of the improvement, showing subsequent steps in the formation of the fabric; Fig. 18 is an enlarged perspective view of the crossed 40 ground warp threads and the pile thread in one position for forming a Persian knot; Fig. 19 is a like view of the same, showing a subsequent position in the formation of the knot; Fig. 20 is an enlarged perspective view of the weave and the lay in beating-in position; and Fig. 45 21 is an enlarged plan view of the finished weave.

In the fabric (Fig. 21) to be woven by the loom illustrated in the drawings, the ground warp threads a , a' are arranged in pairs, and the pile threads b , arranged in sets, are each interwoven with a pair of ground warp threads a and a' , to form a Persian knot, and suitable weft threads c (preferably three) are interwoven with the ground warp threads a , a' between adjacent sets of pile threads b , to insure the formation of a weave of

the oriental rug type, having Persian knots. As is well known, the pile thread b in a Persian knot passes 55 under the ground warp thread a , then over to the top of the other ground warp thread a' and then completely around this ground warp thread a' ; for the pile-end b' to extend up between the ground warp threads a and a' and the pile-end b^2 to extend up on the outside of the 60 ground warp thread a .

In producing the desired result, the ground warp threads a , a' are first crossed (see Fig. 18), and the pile thread b is passed around the crossed portion in a longitudinal direction, then the ground warp threads a , a' 65 are returned to their normal, approximately parallel position, (see Fig. 19) then the first weft thread c is passed through the open shed in the rear of the pile thread b , after which the first weft thread c and the pile thread b are beaten up, to form the Persian knot (see 70 Fig. 20). The other two weft threads are then successively placed in the shed and beaten in, but it is evident that any desired number of weft threads may be used between adjacent sets of pile threads.

In order to produce the weave as described, the following arrangement is made: On a suitably constructed main frame A is mounted the usual warp beam (or beams) B, from which unwind the ground warp threads a , a' , to then extend forwardly and pass over a tension-rod C and through heddles D, D' respectively, and 80 finally to the fabric d, passing over a breast-beam E arranged on the front end of the main frame A. After each third pick a different set of pile threads b is used, each set of pile threads b being carried by tuft yarn tubes F, and each set of tuft yarn tubes F is held on a 85 tuft yarn frame removably mounted on an endless carrier of the usual construction and common in Axminster looms, so that further showing and description of this part of the machine is not deemed necessary, it being understood, however, that after each third pick a frame 90 and its set of tuft yarn tubes F is disconnected from the carrier, transferred to the place for forming the knots (adjacent to the breast-beam E, see Fig. 6), and after the knots are formed the frame and its set of tuft yarn tubes F are returned to the carrier, and the latter is 95 caused to travel, to move the following frame into active position, the carrier traveling in unison with the movement of the loom.

The pile threads b of a set of pile warp threads project somewhat beyond the terminals of their tuft yarn tubes 100 F; and when the loom is in operation the needle-frame is rocked (see dotted positions, Fig. 6), to swing each needle and its pile thread b down between the corresponding ground warp threads a , a' of a pair of ground warp threads, so as to engage the free projecting ends of 105 the pile threads with the clamping ends of a looper G,

employed for looping the pile threads around the crossed warp threads a, a' , the said looper G operating in conjunction with the lay H and with a pair of shogging combs I, I', employed for shifting the ground warp threads a, a' in an approximately horizontal plane, as hereinafter more fully described.

The weft threads c are passed through the open shed at the proper time by a shuttle or the like of a weft-inserting device J (see Fig. 2).

- 10 The tension-rod C is preferably mounted on arms C', attached to a shaft C² journaled on the main frame A, and on the said shaft C² is secured an arm C³, pressed on by a spring C⁴ connected with the main frame A (see Fig. 1), to press the rod C in an upward direction, to 15 give the desired tension to the ground warp threads a, a' . The heddles D, D' are hung in the usual manner on heddle-levers D² and D³, connected with suitable cam mechanism, actuated from the main shaft of the loom, to shift the heddles at the proper time and as herein- 20 after more fully described.

The looper G is hung at its rear end on a crank-shaft K, journaled in suitable bearings A' on the main frame A, and on one end of the said crank-shaft K is secured an arm K', connected with a suitable cam mechanism 25 for imparting an intermittent rocking motion to the crank-shaft K, to swing the looper G forward and backward in a longitudinal direction, an up and down swinging motion being at the same time given to the said looper, and for this purpose the front end of the 30 looper is pivotally connected by links K² with arms K³, attached to a transverse shaft K⁴ journaled in suitable bearings in the sides of the main frame A. On the shaft K⁴ is arranged an arm K⁵, connected with suitable cam mechanism operating in conjunction with 35 the cam mechanism for the arm K', so that when the loom is in motion the looper G is swung from its approximately horizontal position, below the warp threads and the fabric rearwardly and upwardly into an approximately vertical position and back again to 40 its normal position, as hereinafter more fully described.

The lay H is journaled at its lower end by its shaft H' in the sides of the main frame A, and on one end of the said shaft H' is arranged an arm H², connected 45 with suitable actuating mechanism on the loom, so that when the latter is in motion an intermittent forward and backward swinging motion is given to the said lay H.

The shogging combs I and I' are mounted to slide 50 up and down and transversely in suitable guideways A² forming part of the main frame A, and in order to give the said shogging combs the desired motion the following arrangement is made: The upper shogging comb I is hung on links L, pivotally connected at 55 their upper ends with arms L' projecting forwardly from a transverse shaft L² journaled in suitable bearings on the main frame A, and from the said shaft L² extends rearwardly an arm L³, connected by a link L⁴ with a transversely extending rocking lever N, fulcrumed at N' on the main frame A (see Figs. 1 and 2). One end of the rocking lever N is connected by a link 60 N² or other mechanism with a cam device driven from the main shaft of the loom, so that an intermittent rocking motion is given to the lever N. The other or 65 lower shogging comb I' is pivotally connected by links

L⁵ with arms L⁶ attached to a transverse shaft L⁷ journaled on the main frame A, and on the said shaft L⁷ is secured a rearwardly-extending arm L⁸ pivotally connected by a link L⁹ with the rocking lever N, the links L⁹ and L⁴ being pivotally connected with the said 70 rocking lever at opposite sides of the fulcrum N', so as to insure a uniform up and down movement of the shogging combs I and I' whenever the lever N is rocked, as above mentioned.

When the shogging comb I is in a raised, inactive 75 position and the shogging comb I' is in a lowered inactive position, then they are held in left and right hand positions by springs O and O', preferably connected with the links L and L⁵ respectively and the main frame A. The left hand end of the shogging comb I 80 abuts against a vertically-disposed bar P, fixed on the main frame and provided at its lower end with an incline P', so that when the shogging comb I moves downward, then its left-hand beveled end I² engages the incline P' and consequently the shogging comb I 85 is moved from the left to the right while descending. In a like manner the shogging comb I' has its right-hand end provided with a bevel I³, adapted to engage an incline P³ on a bar P² fixed to the right-hand side of the main frame A. Thus, when the shogging comb 90 I' is moved upward its bevel I³ moves in engagement with the incline P³ and consequently the shogging comb I' during its upward movement, is shifted from the right to the left, that is, in an opposite direction to the transverse movement of the shogging comb I. The 95 shogging combs I and I' are provided on their opposite edges with the usual spaced pins or teeth I⁴ and I⁵ (see Figs. 9 and 11), of which the pins I⁴ are adapted to engage the corresponding ground warp threads a and the pins I⁵ are adapted to engage the correspond- 100 ing ground warp threads a' .

When the loom is in operation and the shogging combs I and I' are moved toward each other, then the shogging comb I engages the ground warp threads a while the shogging comb I' engages the ground warp threads 105 a' , and then a transverse movement of the shogging combs takes place in opposite directions, so as to shift the ground warp threads a and a' in a transverse direction with a view to cross the said ground warp threads of each pair, as will be readily understood by reference to 110 Fig. 9. When the shogging combs I and I' move from each other, that is, the shogging comb I upward and the shogging comb I' downward, then the shogging combs are also moved transversely back to their former positions by the action of the springs O and O'. In doing 115 so the shogging combs allow return of the ground warp threads a and a' to their former position, and finally disengage the same, to remain in normal, inactive uppermost and lowermost positions respectively, until the next action. It is understood that the ground warp 120 threads a, a' are under tension and are diverted from their normal parallel position by the shogging combs I and I'; and when the said ground warp threads a, a' are released by the shogging combs, then their tension 125 serves to restore them to their normal approximately parallel position.

The detail construction of the looper G is as follows: Pairs of clamping bars G' and G² are spaced apart, corresponding with the tuft yarn tubes F carrying the pile threads b of a set, and the pairs of clamping bars are 130

adapted to pass between the ground warp threads a, a' of a pair, as will be readily understood by reference to Fig. 11. Each pair of clamping bars G', G^2 is formed at its terminal and at the lower corner with a mouth G^3 (see Fig. 4A) for the ready entrance of the corresponding tuft yarn tube F , to deliver the pile thread b between the clamping bars G' and G^2 on the withdrawal of the tuft yarn tube, so that the free end of the pile thread b is clamped between the terminals of the corresponding pair of clamping bars G' and G^2 .

The clamping bar G^2 is provided a distance from its terminal and at the top with a transversely-extending lug G^4 , reaching into a recess formed in the upper edge of the other clamping bar G' , and over this lug G^4 is drawn the clamped end of the pile thread b after the pile warp thread has been looped around the crossing, as hereinafter more fully explained, and shown in Fig. 12.

The lay H (see Figs. 3, 9, 11 and 20), is provided with alternately arranged long and short dents or reed-bars H^3, H^4 , of which the adjacent long dents H^3 are rigidly connected with each other at their upper ends by a cross-bar H^5 , but this part of the construction is not essential. The short dents H^4 are in longitudinal alinement with the pairs of clamping bars G', G^2 , as will be readily understood by reference to Fig. 11, from which it will be seen that the short dents H^4 pass between the warp threads a, a' of a pair, while the long dents H^3 extend between adjacent pairs of ground warp threads.

The operation is as follows: In Figs. 5, 6, 8, 10, 12, 13 and 17 the ground warp threads a , and a' are, for the sake of clearness, shown one slightly above the other, while in practice the ground warp threads are arranged in the same lateral plan until shifted by the heddles, as hereinafter more fully explained. When the several parts are in the starting position shown in Fig. 5, then the lay H is in a rearmost position, with the dents H^3 and H^4 between adjacent ground warp threads, the looper G is below the breast-beam E and a set of tuft yarn tubes F is now descending from the carrier, and this set of tuft yarn tubes swings down (see different positions in dotted lines in Fig. 6) in such a manner that each tuft yarn tube F with its pile thread b passes between the ground warp threads a, a' of a corresponding pair of ground warp threads, and the tuft yarn tube opens the corresponding pair of clamping bars G' and G^2 of the looper G and delivers the free end of the pile thread b to the said clamping bars G' and G^2 , which thus clamps this end of the pile thread b (see Fig. 6). The set of tuft yarn tubes F now rise straight up to a distance above the ground warp threads, and in doing so the pile threads b are unwound from their spools on the tube-frame and are held stretched in a vertical position between the ground warp threads a, a' of the several pairs, as shown in Fig. 6. When this has taken place both heddles D, D' move upward, the heddle D to its extreme uppermost position and the heddle D' only a distance sufficient to lift the ground warp threads a' , above the upper ends of the short dents H^4 of the lay H (see Fig. 7). The shogging combs I and I' now move toward each other and sidewise, in opposite directions, to cross the ground warp threads a, a' of each pair, the crossing a^2 being at a point between the pile threads b and the short dents H^4 of the lay H , as will be read-

ily understood by examining Figs. 8 and 9. The lay H now swings forward to an approximately vertical position, so that the short dents H^4 pass between the ground warp threads a, a' and thereby move the crossing a^2 of the ground warp threads further downward (see Fig. 11). The looper G is now caused to move rearwardly and upwardly (see Figs. 10, 11 and 12), so that the terminals of the pairs of clamping bars G' and G^2 pass up between the ground warp threads a, a' , immediately in front of the short dents H^4 of the lay (see Fig. 11), and as the looper G rises it carries the ends of the several pile threads b along, thus looping the pile threads b around the crossing a^2 in a longitudinal direction, that is, in the direction of the length of the warp. The looper G , in rising, also swings forwardly, thus causing the pile threads b to move the crossings a^2 further forward, at the same time drawing the loops of the pile threads b tightly around the crossings a^2 . As the loops of the pile threads b are drawn tightly and the looper still rises, it is evident that the free ends of the pile threads b are pulled out from between the clamping bars G', G^2 (see Fig. 12), and then the looper G swings downward and forward, back to its normal position (see Fig. 13). The lay H now returns to its rearmost position and the shogging combs I, I' return to their normal positions, and in doing so they release the ground warp threads a, a' which, by their tension, return into a parallel position (see Fig. 14). The heddles D, D' now shift, that is, the heddle D' moves to its extreme upper position, to carry the ground warp threads a' above the terminals of the short dents H^4 , and the heddle D moves to its extreme lower position, to carry the ground warp threads a below the terminals of the short dents H^4 . The shuttle of the weft-carrying mechanism J now passes the weft thread c through the open shed, in front of the lay H (see Fig. 15), and then the lay H swings forward to its full extent, to beat-in the pile threads b and the weft thread c (see Fig. 16). The lay H then returns to its rearmost position, and during this time a cutting apparatus, such as two knives Q, Q' , is brought into action, to cut off the pile threads b a desired distance above the fabric d and a distance below the terminals of the tuft yarn tubes F , to leave a projecting end at each tuft yarn tube, which projecting end of the pile thread is clamped by the clamping bars G', G^2 on a subsequent act and as above explained. After cutting the pile threads b the knives Q, Q' are moved back to an inactive position, then the heddles change, the next weft thread c is passed through the open shed, and finally beaten in, and this operation is repeated if more weft threads are to be interwoven with the ground warp threads a, a' . As shown in Fig. 21, three weft threads c are shown interwoven with the ground warp threads a, a' between successive sets of pile threads b . After the last weft thread is interwoven the heddles D, D' move to their starting position (see Figs. 5 and 17), and the above-described operation is repeated.

From the foregoing it will be seen that a set of pile threads b is formed into Persian knots on the pairs of ground warp threads a, a' by first passing the pile threads between the threads of the pairs of ground warp threads, then crossing the threads of each pair of ground warp threads, then looping the pile threads

around the crossings of the ground warp threads in the direction of the length of the warp, and then returning the ground warp threads to the first or parallel position, as will be readily understood by reference 5 to Figs. 18, 19 and 20.

It is further understood that the several mechanisms described for producing the desired result operate in unison and are driven from the main shaft of the loom, and as the means for actuating the several mechanisms 10 from the main shaft may be of any approved construction, it is not deemed necessary to further illustrate or describe the same.

I do not limit myself to any detail construction of any one of the several mechanisms employed for producing the desired result, as the same may be varied 15 without deviating from the invention.

Having thus described my invention, I claim as new and desire to secure by Letters Patent:

1. A loom for interweaving a pile thread with a pair of ground warp threads, comprising means for passing a pile 20 thread between a pair of ground warp threads, means for crossing the ground warp threads to one side of the pile thread, means for looping the pile thread around the crossing of the said ground warp threads, in the direction of the length of the warp, and means for returning the said ground warp threads to a parallel position.

2. A loom for interweaving a pile thread and weft threads with a pair of ground warp threads, comprising means for passing the pile threads between the pair of ground warp threads at an angle thereto, means for crossing the ground warp threads at one side of the said pile 30 thread, means for looping the pile thread around the crossing, in the direction of the length of the warp, means for returning the said ground warp threads to a parallel position, means for shifting the ground warp threads to open the shed, means for passing the weft thread through the open shed, and means for beating in the weft thread and the pile thread.

3. A loom for interweaving a pile thread with a pair of ground warp threads, comprising a tuft yarn tube carrying a pile thread and adapted to pass between the ground warp threads, a looper having means for holding and releasing the free end of the pile thread carried by the tuft 40 yarn tube, the said tuft yarn tube and looper standing above and below the said ground warp threads, to hold the pile thread at an angle to the ground warp threads, means for crossing the said ground warp threads at one side of the said pile thread, and means for moving the said looper, to loop the pile thread around the crossing of the ground warp threads and pass the free end of the pile 45 thread up between the ground warp threads and on the other side of the crossing, and releasing the free end of the pile thread from the said looper.

4. A loom for interweaving a pile thread with a pair of ground warp threads, comprising a tuft yarn tube carrying a pile thread and adapted to pass between the ground warp threads, a looper having means for holding and releasing the free end of the pile thread carried by the tuft 50 yarn tube, the said tuft yarn tube and looper standing above and below the said ground warp threads, to hold the pile thread at an angle to the ground warp threads, means for crossing the said ground warp threads at one side of the said pile thread, means for moving the said looper, to loop the pile thread around the crossing of the ground warp 55 threads and pass the free end of the pile thread up between the ground warp threads, on the other side of the crossing, and releasing the free end of the pile thread from the said looper, and means for returning the said ground warp threads to parallel position.

70 5. A loom for interweaving a pile thread with a pair of ground warp threads, comprising a tuft yarn tube carrying a pile thread and adapted to pass between the ground warp threads, a looper having means for holding and releasing the free end of the pile thread carried by the tuft 75 yarn tube, the said tuft yarn tube and looper standing above and below the said ground warp threads, to hold the pile

thread at an angle to the ground warp threads, means for crossing the said ground warp threads at one side of the said pile thread, means for moving the said looper, to loop the pile thread around the crossing of the ground warp threads and pass the free end of the pile thread up between the ground warp threads, on the other side of the crossing, and releasing the free end of the pile thread from the said looper, means for returning the said ground warp threads to a parallel position, heddles for manipulating the said ground warp threads, and a weft-carrying mechanism for passing a weft through the open shed. 80 85

6. A loom for interweaving a pile thread with a pair of ground warp threads, comprising a tuft yarn tube carrying a pile thread and adapted to pass between the ground warp threads, a looper having means for holding and releasing the free end of the pile thread carried by the tuft 90 yarn tube, the said tuft yarn tube and looper standing above and below the said ground warp threads, to hold the pile thread at an angle to the ground warp threads, 95 means for crossing the said ground warp threads at one side of the said pile thread, means for moving the said looper, to loop the pile thread around the crossing of the ground warp threads and pass the free end of the pile 100 thread up between the ground warp threads, on the other side of the crossing, and releasing the free end of the pile thread from the said looper, means for returning the said ground warp threads to a parallel position, heddles for manipulating the said ground warp threads, a weft-carrying mechanism for passing a weft through the open shed, 105 and a lay for beating-in the said weft and the pile thread.

7. A loom for interweaving a pile thread with a pair of ground warp threads, comprising a tuft yarn tube carrying a pile thread and adapted to pass between the ground warp threads, a looper having means for holding and releasing the free end of the pile thread carried by the tuft 110 yarn tube, the said tuft yarn tube and looper standing above and below the said ground warp threads, to hold the pile thread at an angle to the ground warp threads, means for crossing the said ground warp threads at one 115 side of the said pile thread, means for moving the said looper, to loop the pile thread around the crossing of the ground warp threads and pass the free end of the pile thread up between the ground warp threads, on the other side of the crossing, and releasing the free end of the pile 120 thread from the said looper, means for returning the said ground warp threads to a parallel position, heddles for manipulating the said ground warp threads, a weft-carrying mechanism for passing a weft through the open shed, 125 and a lay for beating-in the said weft and the pile thread, and a cutting device for cutting off both ends of the pile thread.

8. A loom for interweaving a pile thread with a pair of ground warp threads, comprising a tuft yarn tube carrying a pile thread and adapted to pass between the ground warp threads, a looper having means for holding and releasing the free end of the pile thread carried by the tuft 130 yarn tube, the said tuft yarn tube and looper standing above and below the said ground warp threads, to hold the pile thread at an angle to the ground warp threads, means for crossing the said ground warp threads at one side of the said pile thread, means for moving the said looper, to loop the pile thread around the crossing of the ground warp threads and pass the free end of the pile 135 thread up between the ground warp threads, on the other side of the crossing, and releasing the free end of the pile thread from the said looper, means for returning the said ground warp threads to a parallel position, heddles for manipulating the said ground warp threads, weft-carrying mechanism for passing a weft through the open shed, 140 a lay for beating-in the said weft and the pile thread, and a cutting device for cutting off both ends of the pile 145 thread a distance above the fabric and a distance below the tuft yarn tubes.

9. A loom for producing an oriental fabric having Persian knots, comprising heddles for the ground warp threads arranged in pairs, an intermittently-reciprocating lay having alternating long and short dents, each short dent being adapted to pass between the ground warp threads of a pair of ground warp threads, a set of tuft 150 yarn tubes for carrying the pile threads and adapted to 155 pass between the ground warps of the pairs of ground warp

mechanism for inserting a weft in the open shed of the ground warp threads, the said weft being beaten together with the pile threads previously formed and interlooped with the ground warp threads.

- 5 18. A loom for weaving pile fabrics, comprising heddles for manipulating the ground warp threads arranged in pairs, a lay having alternately-arranged short and long dents, the short dents being adapted to pass between the ground warp threads of a pair and the long dents extending 10 between adjacent pairs of ground warp threads, a set of tuft yarn tubes carrying the pile threads, means for swinging the said tuft yarn tubes downward, to pass the same between the ground warp threads of the pairs of ground warp threads and for causing the needles to rise 15 vertically, a looper receiving the free ends of the pile threads from the tuft yarn tubes, below the ground warp threads, a shogging device for crossing the ground warp threads between the lay and the pile threads and to allow the ground warp threads to return to a parallel position, 20 means for imparting a rearward and upward and return

movement to the said looper, to carry the pile threads around the crossings of the ground warp threads and up between the ground warp threads of the pairs of ground warp threads at a point between the crossing and the lay, to release the free ends of the pile threads above the 25 ground warps and to return to a normal, inactive position below the ground warp threads, a shuttle mechanism for inserting a weft in the open shed of the ground warp threads, the said weft being beaten in together with the pile threads previously formed and interlooped with 30 the ground warp threads, and a cutting device for cutting off the ends of the said interlooped and beaten in pile threads.

In testimony whereof I have signed my name to this specification in the presence of two subscribing witnesses. 35
